BENDING MACHINE

Robert A. Gifford, Raleigh, Tenn.

Application March 22, 1940, Serial No. 325,275

10 Claims. (Cl. 153—56)

This invention relates to improvements in machines for arcuately curving angle irons, and particularly to machines adapted to curve such irons and concurrently at option incline or straighten up the legs of the angles relatively to the plane in which such bending is done to accomplish a conical or frusto-cylindrical structure.

In bending or straightening angles and other shapes it is well known to use three sets of rollers having substantially parallel axes and to adjust the positioning of the center one of these axes relatively to the other two thereof, in order to accomplish either bending or straightening as the case may be. Some of these machines have additional means for contacting the sides or edges of the angle in a plane at right angles to the plane of the bend to insure that the resulting bent angle has one plane and one cylindrical surface. It is also well known in bending and straightening mills to have rolls with frusto-conical surface at right angles one to the other, and to provide means for driving certain of the rolls.

The objects of the present invention are:

To provide a bending machine which is adjustable to accomplish the arcuate curving of an angle iron to any desired radius.

To provide a bending machine which will bend an angle with one leg radially inward, or radially outward and the other leg upward or downward therefrom, to desired curvature.

To provide a bending machine which may be adjusted to bend an angle to desired curvature with one leg lying substantially along a plane and the other leg thereof cylindrically curved, or which at option may be adjusted to curve said angle with its legs lying along complementary frusto-conical surfaces.

To provide a bending machine having three pairs of rolls, one of said pairs being adjustable relative to the other, in which the three pairs of rolls are driven at equal speeds.

To provide a bending machine having rolls in pairs relatively adjustable for angle thickness, and having one pair of said rolls adjustable relatively to the other pairs thereof in directions at right angles to each other to respectively vary the curvature of the arc along which said angle is rolled and accomplish a desired inclination of the legs of said angle to the plane of the arc in which said angle is rolled.

To provide in an angle bending machine means for adjusting the angular inclination of the legs of the angle with respect to the plane of curvature; and

To provide means for driving the bending rolls, and means for coordinating the speed at which the rolls are driven.

The means by which the foregoing and other objects are accomplished, and the manner of their accomplishment will readily be understood from the following specification on reference to the accompanying drawings, in which:

Fig. 1 is a sectional elevation taken along the transverse center line of the machine, being the line I—I of Fig. 2, showing the means for adjusting the positioning of the center set of rolls to accomplish bending, the means for adjusting the rolls to accomplish variation in the angle of inclination of the legs of the angle, and the means for driving the rolls.

Fig. 2 is a plan view of the machine.

Fig. 3 is a sectional elevation of the machine on the line III—III of Fig. 4.

Fig. 4 is a sectional plan of the machine taken on the line IV—IV of Fig. 3.

Figs. 5 and 6 are sectional side elevations of an angle bent into a ring with the legs of the angle inclined to the plane of curvature, the horizontal leg of the angle being turned outward and the vertical legs upward and downward respectively.

Figs. 7 and 8 are corresponding views showing the angle bent to substantially the same curvature, but with the horizontal legs of the angle turned inward.

Referring now to the drawings in which the various parts are indicated by numerals:

10 is a base having a top 11 in which are turnably mounted a pair of vertically disposed sleeves 12 spaced apart, these sleeves having shoulder portions 13 which rest on the upper surface of the base and support the sleeves, and being retained from longitudinal displacement relative to the base by collars or plates 14 suitably secured to the under end of the sleeve.

Each of the sleeves 12 has an integral frame 15 which is inclined substantially at an angle of forty-five degrees to the axis of the sleeve, in which frame a shaft 16 is suitably journaled. 45 Forming an integral part of, or rigidly secured on, this shaft is a roll 17 having frusto-conical surfaces A, B and C arranged in abutting relation, these surfaces having a cone angle of ninety degrees for standard ninety degree angles, the smaller ends of the surfaces A and B being of equal diameter and abutting and the larger ends of the surfaces B and C being of equal diameter and abutting, such roll types being well known.

55 Cooperating with the roll 17 is a roll 18 having

complementary frusto-conical surfaces, this roll being integral with, or rigidly secured on, a shaft 19 which is parallel to the shaft 16 and is suitably journaled in a journal box 20. The journal box 20 is slidably mounted in the frame 15 for movement toward and away from the shaft 16, this movement being accomplished as by a screw 21 manually operable and being adapted to shift the two rolls closer together or further apart to accommodate various thicknesses of angle iron.

Secured on the shaft 16 is a bevel gear 25 which meshes with a bevel pinion 26. The pinion 26 is secured on a vertical shaft 27 suitably journaled in the sleeve 12, a secondary sleeve 28 being introduced between the shaft 27 and sleeve 12 in order to accomplish the installation of the pinion and its drive. The sleeve 28 is secured against displacement by the plate 14. Secured on the outer end of the shaft 27 is a bevel gear 29, which meshes with a bevel pinion 30, this pinion being suitably secured on a shaft 31 journaled in bearing portions 32, 33 of the frame 10 and extending exterior to the frame 10. Secured on the outer end of the shaft 31, is a gear 34, there being a like gear, similarly numbered, for the opposite drive and an intermediate gear 35 for driving the intermediate rolls, as will be later described.

The drive of one of the gears 34 and the gear 35 is accomplished by a pinion 36 secured on the shaft 37 of an electric motor 38. The remaining gear 34 is driven through the gear 35 and an idler 39, the pinion 36 and the idler 39 being of the same pitch diameter and the gears 34 and the gear 35 being also of equal diameter, though preferably substantially larger than the pinions 36 and 39 to accomplish reduction from the speed of the motor 38.

Disposed between the two sets of rolls 17 and 18 is an intermediate set of rolls 45, 46, these rolls being respectively substantial duplicates of the rolls 17, 18, and like these rolls having shafts 47, 48, the shaft 47 being journaled in a frame 49 inclined in similar manner as are the frames 15, and the shaft 48 being journaled in a suitable box 50 corresponding to the box 20 and manually adjustable along the frame 49 by means of the screw 51 to approach or move the roll 46 toward or away from the roll 45 as before.

Secured on the shafts 16 are gears 16-A, which intermesh with gears 19-A on the shafts 19, the teeth of the gears being of extra length in order that they may intermesh with varied thicknesses of angle interposed between the rolls. The shafts 47 and 48 are similarly provided with intermeshing gears 47-A, 48-A respectively.

The frame 49 has an integral shank 52, here shown substantially rectangular to prevent turning, which is vertically slidable in a carrier 53, the shank 52 having vertical gibs 54, which slide in complementary grooves in the carrier 53 to insure accurate vertical movement. The carrier 53 is slidably mounted for horizontal movement on oppositely disposed horizontal guides or gibs 55 which are parallel to the plane containing the axes of the rolls 45, 46 and permit shifting movement of these rolls in such plane. The carrier 53 is provided with an elongated nut 56 which is rigidly secured thereto against longitudinal displacement, or which may be integral therewith. Threaded into the nut is a screw 57 which is turnably mounted in the front wall of the base 10 and which has collars 58 to prevent its longitudinal displacement. This screw is provided with a head 59 which may be engaged and manu-

ally operated to shift the carrier 53 forward or backward along the guides 55. The shank 52 of the frame 49 is internally threaded, this threading for assembly purposes being in a sleeve 60 which is rigidly secured in the base portion as by a transverse pin 61. Threaded into the sleeve is a hollow screw 62 which is turnably mounted in a transverse part 63 of the carrier 53, the screw 62 having a flange 64 which rests on the member 63 and supports the screw. Secured on the screw below the part 63 is a bevel gear 65 which abuts the underside of the part and prevents upward movement of the screw. The gear 65 meshes with a bevel pinion 66 which is secured on a shaft 67, turnably mounted in a portion of the frame 53. The shaft 67 extends freely through an opening 68 in the front wall of the base 10 and is squared to receive a wrench so that it may be turned to turn the screw and raise or lower the frame 49.

70 is a bevel gear secured on the shaft 67 and adapted to turn the roll 45. Meshing with the gear 70 is a bevel pinion 71 which is secured on a shaft 72 journaled in the hollow screw 62. The lower end of the shaft extends slidably through a bevel gear 73 and is additionally journaled in a bracket 76, 76—A forming part of the carrier 53, the bracket preventing vertical movement of the gear. The shaft 72 has a key-way 72-A with which a spline (not shown) within the hub of the gear 73 slidably engages. The gear 73 meshes with a bevel pinion 74 which is secured on a shaft 75, the shaft being journaled adjacent the pinion 74 in the bracket 76. The shaft 75 extends laterally through and is slidably mounted in the gear 35. The gear carries a spline 77 and the shaft 75 is provided with a complementary key-way 78 in which the spline 77 slides, giving driving connection between the gear 35 and the shaft 75, but permitting sliding movement of the shaft with respect to the gear. The gear 75 is provided with an elongated hub 80 which is journaled in the rear portion of the frame 10.

Through the above construction it is possible to shift the rolls 45 and 46 forward and backward in the plane of their axes and to raise or lower them in the same plane and at the same time accomplish the positive drive of the rolls at the same speed that the rolls 17, 18 are driven.

The side edges of the carrier 53 are provided with rack teeth 82 and the sleeves 12 are provided with arcuate sectors 83 having teeth thereon meshing with the racks 82, the sectors 83 preferably being integral with the sleeves, but at least being rigidly secured thereto. Movement then of the carrier 53 to laterally shift the frame 49 and the rolls 45, 46 turns the sleeves 12 and the frames 15 carried thereby to adjust the angular position of the plane of the roll axes 17, 18 with respect to the plane of the axes of the rolls 45 and 46.

The machine just described is primarily used for bending angle iron. If the angle iron is to be bent to fit a cylindrical surface the center pair of rolls 45, 46 are adjusted vertically to the same level as the rolls 17, 18. The rolls 46 and 18 are moved away from the rolls 45 and 17 respectively. The angle iron 90 is placed in the rolls either with the vertical leg upward, as shown in Fig. 1, or with the vertical leg downward, as shown in Fig. 3. The surfaces A, B of the rolls 17, in Fig. 3, and the corresponding and complementary surfaces of the other rolls being used in the first instance and the surfaces B, C of the rolls 17

and the similar and complementary surfaces of the other rolls being used in the second instance. In either case the rolls are then tightened through the intermediary of the screws 21 and screw 51 to clamp against the angle. The frame 49 carrying the rolls 45, 46 are then shifted horizontally and the motor 38 is started to drive the rolls. As the rolls are turned by the motor the angle iron is traversed in usual manner by the rolls. Should the roll shift be to the right and the horizontal flange extend to the left, the action of the rolls would be to compress this flange and stretch the vertical flange. Should the horizontal leg be in the opposite direction, the action would be to stretch the horizontal leg with compressive strain on the vertical leg, and in either event the curvature accomplished would cause the bent angle 90 to curve outward to the left in a substantially horizontal plane with the vertical leg of the angle cylindrically curved.

Should there be a twist of the plane of curvature to the left of the rolls downward or upward, a downward or upward shift respectively of the center set of rolls would tend to stretch the bottom or top of the angle as the case might be and restore the plane to horizontal.

Should it be desired to form a ring having frusto-conical angle surfaces, the vertical shifting of the rolls to accomplish greater stretch top or bottom as the case may be, is continued until the desired angle is obtained.

In Fig. 5 an angle ring 90—D is shown which has been formed by passing an angle through the rolls as shown in Fig. 1 with the center rolls depressed to establish a 30-60 degree cone angle, the position assumed by the plane of the ring being indicated in Fig. 1 by the dash lines similarly designated, it apparently being clearly evident that if the center rolls be so depressed the lower edge of the vertical leg of the angle will be stretched and thereby lengthened with the obvious resulting coning.

Fig. 6 and Fig. 1 correspondingly show the angle ring 90—E resulting from raising the center rolls in corresponding manner, and in Fig. 7 and Fig. 2, and Fig. 8 and Fig. 2 the corresponding resulting rings 90—F and 90—G are shown.

It will be understood that the 30-60 degree angles shown in the drawings are arbitrarily selected and that any angle from 0-90 degrees to 45-45 degrees may be had by variation in the amount of raising or depression of the center rolls.

It will also be understood that the center set of rolls may not be power rolls, but it has been found that driving them is of obvious advantage particularly where small diameter rings are rolled on where considerable coning is to be effected.

I claim:

1. In an angle bending machine, two roll sets spaced laterally apart, and a third roll set therebetween, each roll set comprising a pair of complementary rolls, each having frusto-conical surfaces, said rolls being suitably journaled on parallel axes inclined in the plane of said axes at an angle of substantially forty-five degrees, means, each mounting an outer said roll set for turning movement about a substantially vertical axis and for restraining movement of said set along said axis, means for supporting said central roll set with the plane of the roll axes transverse to the plane containing the said vertical axes of the outer roll sets, means for shifting said central roll set horizontally in the plane of its roll axes, means cooperating with said shift-

ing means for turning said outer roll sets concurrently in opposite directions about said vertical axes, means for vertically shifting said center roll set relatively to said outer roll sets, and means for driving all of said rolls.

2. An angle bending machine in accordance with claim 1 in which only the outer sets of rolls are driven.

3. In an angle bending machine, two roll sets spaced laterally apart and a third roll set therebetween, each roll set comprising a pair of complementary rolls, having frusto-conical surfaces arranged in undulatory succession, said rolls being suitably journaled on parallel axes inclined in the plane of said axes at an angle of substantially forty-five degrees, means, each mounting an outer said roll set for turning movement about a substantially vertical axis and for restraining vertical movement of said set, means for supporting said central set of rolls against turning movement with the plane of the roll axes transverse to the plane containing the said vertical turning axes of the outer sets of rolls, means for shifting said central set of rolls horizontally in the plane of its said roll axes, means cooperating with said shifting means for turning said outer sets of rolls concurrently in opposite directions about said vertical axes, means for vertically shifting said center set of rolls relatively to said outer sets of rolls, and means for driving said outer sets of rolls.

4. An angle bending machine in accordance with claim 3 in which all three sets of rolls are driven.

5. In an angle bending machine, two roll sets spaced laterally apart and a third roll set therebetween, each roll set comprising a pair of complementary rolls suitably journaled on substantially parallel axes inclined in the plane of said axes, said rolls having frusto-conical surfaces arranged in undulatory succession, means each mounting an outer said roll set for turning movement about a substantially vertical axis and for restraining vertical movement of said set, means for supporting said central roll set against turning movement with the plane of its roll axes transverse to the plane containing the said vertical turning axes of the outer roll set, means for shifting said central roll set horizontally in the plane of its roll axes, means for vertically shifting said center set of rolls relatively to said outer sets of rolls, and means for driving said rolls.

6. In a machine for bending angle irons and the like, the combination of a central unit, including a pair of cooperative rolls having axes lying in a plane, and two complementary side units, each including a pair of cooperative rolls, means for driving at least one of said units, and independent means, for respectively forcibly shifting said central unit in the plane of said axes, in two directions substantially at right angles.

7. In a machine for bending angle irons and the like, the combination of a central unit, including a pair of cooperative rolls having axes lying in a plane, and two side units, each including a pair of cooperative rolls substantially symmetrically disposed with relation to said plane, means for driving at least one of said units, and independent means, for respectively forcibly shifting said central unit in the plane of said axes, in two directions substantially at right angles.

8. In a machine for bending angle irons and the like, the combination of a central unit, including a pair of cooperative rolls having axes

lying in a plane, and two side units, each including a pair of cooperative rolls substantially symmetrically disposed with relation to said plane, means for driving at least one of said units, and independent means, for respectively forcibly accomplishing relative shift of said central and side units, in shift directions substantially at right angles and parallel to the axial plane of said central roller pair.

9. In a machine for bending angle irons and the like, the combination of a central unit, including a pair of cooperative rolls having axes lying in a vertical plane, and two complementary side units, each including a pair of cooperative rolls having axes respectively disposed in vertical planes substantially equally spaced on opposite sides of said central plane, means for driv-

ing at least one of said units, and independent means, for respectively forcibly shifting said central unit in the plane of its axes in two directions substantially at right angles.

10. In a machine for bending angle irons and the like, the combination of a central unit, including a pair of cooperative rolls having axes lying in a vertical plane, and two complementary side units, each including a pair of cooperative rolls having axes respectively lying in planes disposed parallel to and on opposite sides of said central plane, independent means for shifting said central unit respectively in two directions substantially at right angles, in said vertical plane, and means for driving said rollers.

ROBERT A. GIFFORD.
